BRACKET CLAMP

Filed May 9, 1939

FIG. 5

INVENTOR.
PAUL N. CLOUTIER
BY *Harry Lea Dodson*.
ATTORNEY.

UNITED STATES PATENT OFFICE

2,220,214

BRACKET CLAMP

Paul N. Cloutier, Decatur, Ill., assignor to Faries Manufacturing Company, Decatur, Ill., a corporation of Illinois

Application May 9, 1939, Serial No. 272,551

1 Claim. (Cl. 24—243)

My invention relates more specifically to clamps which are designed to hold a bracket to support a lamp, though it will be clear to those persons skilled in the art that it can readily be adapted for various applications where the need arises.

Clamps of this type, with which I am familiar, are designed to clamp on a square edged desk with ample room for the clamping plate to frictionally engage the inner surface of desk or table edge. The result of this construction is that when one wishes to clamp the bracket on the edge of one of the newer and more modern types of desks or tables constructed usually of metal with a round, bevelled or moulded edge, the clamp will not hold.

My invention has for its principal object to provide a clamp which will secure the bracket firmly in the desired position, regardless of the curvature or configuration of the edge of the desk or table to which it is to be fastened.

A further object is to so construct the clamp that it will be adaptable to various thicknesses of the top as well as the configuration of the edge of the desk or table.

A further object is to so construct the clamp that although it will hold the bracket securely at all times, it will not mar the top of the desk or table at all.

My means of accomplishing the foregoing objects may be more readily understood by having reference to the accompanying drawing which is hereunto annexed and is a part of this specification, in which:

Fig. 1 is a side elevation of my improved clamp showing a lamp bracket mounted on a desk having a round edge type;

Fig. 2 is a view without the bracket and showing a different edge;

Fig. 3 shows my device clamping on a desk having another form of edge;

Fig. 4 is an enlarged side elevation with the clamping plate omitted;

Fig. 5 is a bottom view with the screw shown in cross section; and

Fig. 6 is a perspective view of the clamping plate.

Similar reference numerals refer to similar parts throughout the entire specification.

While for the purposes of this application, I have illustrated my invention to hold a lamp bracket, it will be apparent that such use is but one of many uses to which my invention may be put, and the showing is but for the purpose of disclosing a concrete embodiment of a preferred

form of my invention, and is not at all to be taken as a limitation thereon.

As shown in the drawing, a fragmentary outline of a section of a table or desk edge 1 only is shown, since obviously the table or desk forms no part of my invention. My clamp which is secured to the portion 1 comprises a vertical or body portion 2 which is preferably formed integral with a front or top portion 3 which extends at substantially right angles to the body 2. 10

In practice it may be found desirable to cover the lower surface 4 of the front portion 3 with a layer of felt or other similar material to protect the top of the desk. The lower end 5 extends inwardly and is provided with a hand screw 6 15 which is mounted in a threaded opening formed in the lower end 5. The body 2 is formed with two vertical wings or walls 7 and 8 which extend laterally from the body 2 of the clamp. A plurality of slots 9 and 10 are formed in the walls 7 20 and 8 respectively. That portion of the walls which forms the edges of the slots 9 and 10, are slanted, as clearly seen in Fig. 4. A follower plate 11 is formed with legs 12 and 13 designed to rest in the slots 9 and 10. This follower plate 25 11 is provided with a concave or convex socket 14 adapted to receive the end 15 of the screw 6 which is fitted to and coincides with the socket 14. This socket 14 is preferably located nearer the body portion 2 than the outer edge of the 30 follower plate 11. A rod or handle 17 is mounted in the other end 18 of the screw 6 for its convenient manipulation. The operation of the clamp is as follows: The screw 6 is retracted and the follower plate 11 is placed in position. The 35 legs 12 and 13 being inserted into the slots 9 and 10 which are suitable to clamp the desk or table top of corresponding thickness. The end 15 of the screw 6 is then placed in the socket 14 and the screw 6 is rotated by its handle 17. This 40 tips the follower plate 11, as clearly seen in Figs. 1, 2 and 3, instead of moving it upwardly in a horizontal plane, causing its edge 19 to engage the lower surface of the desk or table edge. The result is that a very slight pressure upon the 45 handle 17 will fasten the clamp so firmly on the desk, whether it be steel or wood, that it cannot be accidentally dislodged, yet it can be easily removed by retracting the screw 6.

I have shown the body portion 2 constructed 50 to support a lamp bracket 21, but as explained, it can be shaped to support any kind of a bracket.

Having described my invention what I regard as new and desire to secure by Letters Patent is:

A device of the character described comprising

ing vertically extended body portion having a horizontal extension at one end thereof, the lower surface of which is smooth, a smaller extension at the other end and two laterally extending vertical wings having a plurality of transverse slots in their edges, the surfaces of which are slanted, a plate provided with two legs

to fit loosely in said slots, a screw having a conoidal end mounted in the lower extension being a socket in said plate in which the end of said screw fits whereby rotating said screw will cause the edge of said plate to engage the article to be clamped. 5

PAUL N. CLOUTIER.
